TANK DRAIN

Gwynne Raymond, Oklahoma City, Okla.

Application May 16, 1938, Serial No. 208,153

6 Claims. (Cl. 210—209)

This invention relates to drain fittings and particularly to a drain for liquid storage tanks where it is desirable to draw off the bottom liquids or sediment without carrying off or agitating the upper contents of the tank, or stirring up the bottom liquids.

The principal objects of the invention are to provide a drain of this character which is of simple construction and assembly so that it may be readily installed in a side wall or staves of a tank; to provide a drain having an unobstructed inlet or mouth so that the bottom liquids flow freely across the tank bottom and carry therewith any sediment without agitation; to provide a drain with a box-like shield attached to and carried by the drain fitting so as to avoid vortexes in the liquid as it flows into the drain fitting; and to provide a drain fitting that is installed independently of manhole covers or other tank fittings.

In accomplishing these and other objects of the invention, I have provided improved details of structure, the preferred form of which is illustrated in the accompanying drawing, wherein:

Fig. 1 is a perspective view of the bottom portion of a storage tank equipped with a drain constructed in accordance with the present invention, the wall of the tank and a portion of the box-like shield of the drain being broken away to better illustrate the assembly.

Fig. 2 is a vertical section through a portion of the tank and drain.

Fig. 3 is a detail perspective view of the parts of the drain fitting shown in disassembled spaced relation.

Fig. 4 is a perspective view of the box-like shield for preventing formations of vortexes in the liquid.

Referring more in detail to the drawing: Fig. 1 designates a liquid storage tank such as used in storing liquids which may contain extraneous matter of heavier specific gravity, such as water, or sediment that settles to the bottom of the tank, and which is to be drawn off without disturbing the liquid contents of the upper portion of the tank, or which is removed prior to drawing off of the upper liquids.

The tank is shown as comprising a bottom 2 and an annular wall 3 that may be formed of sheet metal plates or wooden staves in accordance with standard tank practices. Formed in the side wall of the tank, at a point spaced slightly above the bottom thereof, is an opening 4 for receiving a drain fitting 5 embodying the features of the present invention. The drain fit-

ting 5 includes a hollow, elbow-like body having a tubular neck 6 projecting from an annular collar 7 which forms a stop shoulder 8. The fitting 5 also includes a downwardly sweeping portion 9 terminating in a downwardly opening mouth or inlet 10 that is spaced from the collar 7 and located at substantially right angles to the axis of the neck 6, the mouth 10 being preferably inscribed by a reinforcing bead 11.

The neck 7 is of sufficient length to extend through the wall of the tank and accommodate a packing ring 12 and a nut 13 having internal threads 14 for engaging external threads 15 on the neck and having gripping lugs 16 on the periphery thereof for facilitating application of the nut. Also formed as a part of the neck and extending therefrom is a reduced cylindrical extension 17 having lugs 18 adapted to be engaged by a suitable wrench (not shown) for retaining the fitting from rotation as later described. The lugs 18 may be of any suitable shape but are preferably no higher than the annular face of the neck portion 6 so that they pass readily through the tank opening 4.

The extension 17 is internally threaded, as at 19, to accommodate the threaded end 20 of a drain pipe 21. In order to avoid vortexes in the liquid flowing from the tank into the mouth 10, the fitting is covered with a box-like shield 22, having side and end walls 23—24 and 25—26 connected by a top 27 to form an enclosure about the drain fitting. The lower edge of the wall 26 has spaced feet 28 and 29 that are adapted to engage the bottom of the tank and cooperate with the fitting in supporting the lower edges 30 of the side and end walls in spaced relation with the tank bottom to form inlets 31 through which liquid and the like flows into the shield 22 for flow through the mouth 10 into the drain pipe 21 whenever the drain pipe is opened to establish the flow as in conventional practice.

The end wall 25 has an arcuate shaped notch 32 opening upwardly from the lower edge thereof so that the side edges 33 and 34 are adapted to engage in an arcuate slot 35 that is formed in the upper portion of the collar 7 as best shown in Fig. 3. A part of the end wall 25 directly above the notch is turned outwardly into the plane of the top 27 to form an ear 36 adapted to overlie a flattened lug 37 that is formed on the upper side 50 of the collar, as best shown in Figs. 1 and 2. The ear 36 has an aperture 38 aligning with a threaded socket 39 in the flat face of the lug.

Extending over the ear 36 is a reinforcement strap 40 having an opening therein registering 55

with the opening 38 and through which a fastening device, such as a cap screw 41 is inserted and threaded into the socket 39 for tightening the ear thereagainst and retaining the shield in fixed relation with the drain fitting.

5 In assembling a drain of the character described, an opening 4 is provided at the desired location in the wall of the tank and of sufficient diameter to pass the neck 6 of the fitting 5. The fitting 5 is then applied from the interior of the tank so that the neck 6 thereof projects through the opening 4 and the shoulder 8 of the collar 7 engages the inner face of the tank wall. The gasket ring 12 is then sleeved over the neck of 15 the fitting and moved into engagement with the exterior face of the tank wall. The nut 13 is then applied to the threads 15 and tightened against the packing ring 12 to effect a liquid-tight seal about the neck of the fitting. During tightening of the nut 13 the lugs 18 on the extension 17 may be gripped by a suitable wrench to prevent rotation of the fitting so that the mouth thereof is kept in facing relation with the bottom 2 of the tank as shown in Fig. 2. The box-like 20 shield 22 is then applied to the fitting so that the notch 32 thereof engages in the slot 35 of the collar 7 and the foot portions 28 and 29 engage the bottom of the tank. The cap screw 41 is then applied to anchor the box-like shield in position. The drain pipe 21 is then screwed into the threads 19 to complete the assembly. When flow is established through the drain pipe, liquid in the bottom of the tank drains first and flows quiescently across the bottom 2 through the ports 31 below the edges 30 of the shield and into the mouth 10 for discharge through the drain pipe. The box-like shield 22 prevents formation of vortexes in the liquid flowing into the mouth of the fitting and prevents channelling of the upper 25 liquid through the lower liquid and any sediment that might be contained in the bottom of the tank because there is no direct flow of the liquids, since the liquids must first pass through the openings 31 of the shield before gaining entrance to the mouth 10 of the fitting 5. The lateral movement of the removed liquid passing under the shield keeps the bottom of the tank surrounding the mouth of the fitting clean and free of obstructions so as to avoid any agitation 30 of the upper contents of the tank.

From the foregoing it is apparent that I have provided a relatively inexpensive and simple drain fitting that is readily installed in the wall of a tank.

55 What I claim and desire to secure by Letters Patent is:

1. A drain for tanks including a fitting having a mouth portion and a laterally extending neck adapted to extend through an opening in the wall 60 of a tank, a collar on the neck engaging said wall, a clamping member on the neck cooperating with said collar to anchor the fitting, a box-like shield covering the mouth portion of the fitting having downwardly extending walls forming an open bottom, one of said walls having a portion engaging over the neck of the fitting, and foot portions 65 on one of the walls engaging the bottom of the

tank, to cooperate with said fitting in spacing the lower edges of said walls substantially parallel with the bottom of the tank.

2. A drain for tanks including a fitting having a mouth portion and a laterally extending neck 5 adapted to connect with a drain pipe leading from a tank, a box-like shield covering the mouth portion of the fitting having downwardly extending walls and an open bottom, foot portions on one of the walls engaging the bottom of the tank, 10 and means anchoring said shield to the fitting including a groove in the fitting and a notch in one of said walls having edges engaging in said groove.

3. A drain for tanks including a fitting having a mouth portion and a neck adapted to connect with a drain pipe leading from a tank, a box-like shield covering the mouth portion of the fitting having downwardly extending walls and an open bottom, foot portions on one of the walls 20 engaging the bottom of the tank, one of said walls having a notch to pass the fitting, an ear on the shield above said notch, and means securing the ear to the fitting.

4. A drain for tanks including a fitting having a mouth portion and a laterally extending neck adapted to extend through an opening in the wall of a tank, a collar on the neck and having a groove therein, means cooperating with said collar to anchor the fitting in the wall of the tank, a box-like shield covering the mouth portion of the fitting having downwardly extending walls and an open bottom, a footing on one of the walls engaging the bottom of the tank, one of said walls having a notch to pass the fitting, 30 an ear on the shield above said notch, and means securing the ear to the fitting, said collar having a slot to receive edges of the wall about said notch.

5. A drain for tanks including a fitting having a downwardly facing mouth, a laterally extending neck adapted to extend through an opening in the wall of a tank, means on the neck to anchor the fitting in said wall, a box-like shield covering the mouth of the fitting having downwardly extending walls, foot portions on one of the walls engaging the bottom of the tank to space said shield from the bottom of the tank, one of said walls having a notch to pass the fitting, an ear on the shield above said notch, and means 45 securing the ear to the fitting.

6. A drain for tanks including a fitting having a downwardly facing mouth and a laterally extending neck adapted to extend through an opening in the wall of a tank, means on the neck for 55 anchoring the fitting to said wall, a box-like shield covering the mouth of the fitting having downwardly extending walls, foot portions on one of the walls engaging the bottom of the tank to space the shield from said bottom, one of said walls having a notch to pass the fitting, an ear on the shield above said notch, and means 60 securing the ear to the fitting, said fitting having a slot to receive edges of the wall about said notch.

GWYNNE RAYMOND.
